US0D1026561S

(12) **United States Design Patent** (10) **Patent No.:** **US D1,026,561 S**
(45) **Date of Patent:** **** May 14, 2024**

(54) **DRINKING VESSEL**

- (71) Applicant: **PepsiCo, Inc.**, Purchase, NY (US)
- (72) Inventors: **Stefano Benito Giuliani**, Brooklyn, NY (US); **Niklas Gustafsson**, New York, NY (US); **MinSuk Kim**, Brooklyn, NY (US); **Oded Lahav**, Modiin (IL); **Yuri Movshovich**, Ramat Gan (IL); **Adi Raz**, Herzeliya (IL)
- (73) Assignee: **PepsiCo, Inc.**, Purchase, NY (US)
- (**) Term: **15 Years**
- (21) Appl. No.: **29/846,061**
- (22) Filed: **Jul. 13, 2022**

Related U.S. Application Data

- (63) Continuation of application No. 29/770,220, filed on Feb. 10, 2021, now Pat. No. Des. 957,883.
- (51) **LOC (14) Cl.** **07-01**
- (52) **U.S. Cl.** **USPC** **D7/509**
